[57] CLAIM

The ornamental design for machine for cutting workpieces utilizing electric discharge, as shown and described.

DESCRIPTION

FIG. 1 is a front elevational view of a machine for cutting workpieces utilizing electric discharge, showing our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a front, top and right side perspective view thereof.
